UNITED STATES PATENT OFFICE

109,433

DESIGN FOR A CHAIR OR SIMILAR ARTICLE

Bertha Bunder, Brooklyn, N. Y., assignor to Lewis Corey, New York, N. Y.

Application December 23, 1937, Serial No. 73,821

Term of patent 14 years

To all whom it may concern:

Be it known that I, Bertha Bunder, a citizen of the United States, residing in Brooklyn, county of Kings, State of New York, have invented a new, original, and ornamental Design for Chairs or Similar Articles, of which the following is a specification, reference being had to the accompanying drawing, forming part thereof.

The figure is a perspective view of the chair, showing my design.

I claim:

The ornamental design for a chair or similar article substantially as shown.

BERTHA BUNDER.
